UNITED STATES PATENT OFFICE.

WATSON MACKEWEN, OF DETROIT, MICHIGAN.

VEHICLE TOP.

15,392.

Specification of Reissued Letters Patent. Reissued June 20, 1922.

Original No. 1,286,692, dated December 3, 1918, Serial No. 236,258, filed May 24, 1918. Application for reissue filed December 6, 1920. Serial No. 428,802.

To all whom it may concern:

Be it known that I, WATSON MACKEWEN, a citizen of the United States of America, residing at Detroit, in the county of Wayne 5 and State of Michigan, have invented certain new and useful Improvements in Vehicle Tops, of which the following is a specification, reference being had therein to the accompanying drawings.

10 This invention relates to vehicle tops, and the primary object of my invention is to provide a top framework which may be supported by a single rearwardly extending bow and the wind-shield frame of an automobile body, without using additional body bows that may tend to obstruct or interfere 15 with the view of passengers in the automobile, besides lending weight to the same and requiring considerable labor when the top 20 is to be raised or lowered.

Another object of my invention is to provide a vehicle top framework including a rearwardly extending bow, supplemental, intermediate and outrigger bows connected 25 by links and arms in a manner as to provide a rigid framework when the top is set up and a compact framework when the top is folded or collapsed, in either instance the framework being for such construction as 30 to prevent the canopy or cover thereof from being cut or unnecessarily worn when the top is manipulated.

A further object of my invention is to accomplish the above and other results by 35 a simple and durable mechanical construction that will be hereinafter specifically described and then claimed, and reference will now be had to the drawing, wherein—

Figure 1 is a longitudinal sectional view 40 of the top framework, showing the inner side thereof in elevation; and the framework extended or raised;

Fig. 2 is a similar view showing the framework collapsed or folded, and

45 Fig. 3 is a detail sectional view of the telescopic arm adapted to form part of the framework.

In the drawing, the reference numeral 1 denotes a portion of an automobile body 50 having a windshield 2 and a rearwardly extending bow 3, said bow being of a conventional form adapted to be lowered about the rear seat of the automobile body.

On the rearwardly extending bow 3, adja-

cent the top thereof, are two pieces of hardware 4, and as each side of the framework is identical in construction, I deem it only necessary to consider one side of the framework, as shown in Figs. 1 and 2.

The piece of hardware 4 may be in the form of a sleeve or fitting suitably secured to the rearwardly extending bow 3 and provided with an apertured lug 7 and a flange 5 having a series of apertures 6.

Pivots connected to the apertured lug 65 7 is an intermediate break-down bow 8, said intermediate bow having rule or break-down joints 9, so that the rear ends of the bow may be swung downwardly substantially in parallelism with the rearwardly extending bow 3 and the forward end of the bow 8 swung upwardly and rearwardly into parallelism with the ends 10 of said bow.

11 denotes a supplemental bow having the ends thereof pivots connected to a bracket 75 12, carried by the inner side of the intermediate bow 8, at the end 10 thereof, and as shown in Fig. 2 it is possible to swing the supplemental bow 11 rearwardly between the bow 8 and the end 10 thereof.

13 denotes an outrigger bow adapted to have its forward end connected to the wind-shield 2, said outrigger bow having each end thereof pivots connected, as at 14, to a telescopic arm, comprising a compound 85 curved section 15 and a straight tubular section 16. The compound curved section 15 is pivots connected, as at 17, to the intermediate bow 8 adjacent the rule joint 9, and said section terminates in a tubular slotted 90 socket 18 to receive the tubular section 16. The forward end of the tubular section 16 has a transverse pin 19 slidable in the slots 20 of the socket 18, and the rear end of the tubular section is pivots connected to the flange 5 at one of the apertures 6 thereof. It is through the medium of the series of apertures 6 that the rear ends of the telescopic arms may be adjusted so that the forward end of the outrigger bow 13 will be 95 properly held relative to the windshield 2.

21 denotes a compound curved link connecting the inner side of the outrigger bow 13 to the inner side of the intermediate bow 8, and 22 denotes a longer link connecting 105 the inner side of the outrigger 13 to the inner side of the supplemental bow 11, these links cooperating in correctly supporting

the bows 8 and 11 relative to the bows 13 and 3 so that a canopy or cover 23 may be properly held by the top framework.

The manner in which the various bows are 5 articulated provides a cantaliver structure possessing sufficient rigidity, when set up or extended to insure a safe framework for the canopy or cover 23, and when folding or collapsing the framework, the tubular sections 10 of the telescopic arms slide into the sockets 18 so as to reduce the longitudinal dimension of each of the telescopic arms and thus permit of the framework being compactly assembled at the rear end of the automobile body.

In some instances, particularly when the arms and bows are properly proportioned, the arm sections 16 and 17 may be made integral, without the telescopic connection, so 20 that each arm will be as one piece extending from the rearwardly extending or body bow 3 to the outrigger bow 13.

Furthermore, in small tops the framework may simply include the rearwardly 25 extending or body bow 3, the intermediate break-down jointed bow 8, the outrigger bow 13, and side arms connecting the outrigger bow to the rearwardly extending or body bow 3, thus eliminating the supplemental bow 11, links 21 and 22. In such a top the bows and arms are properly proportioned and articulated for easy manipulation when collapsing or setting up the framework.

In using the term bows, I desire it to be 35 understood that said bows include sockets, wooden frames, spacers, and such other elements, which when properly proportioned and assembled, will provide a top framework that may be easily manipulated.

40 One embodiment of my invention has been illustrated, but it is to be understood that the structural elements are susceptible to such variations and modifications as fall within the scope of the appended claims.

45 What I claim is:

1. A vehicle top framework, comprising a rearwardly extending bow, an intermediate break-down bow connected thereto, a supplemental bow connected to said intermediate bow, an outrigger bow, links connecting said outrigger bow to said intermediate bow, links connecting said outrigger bow to said supplemental bow, and telescopic arms connecting said outrigger bow to said rearwardly extending bow and said arms pivotally connected to said intermediate bow.

50 2. A vehicle top framework, comprising a rearwardly extending bow, an intermediate break-down bow pivotally connected to said

rearwardly extending bow, an outrigger 60 bow, links connecting said outrigger bow to said intermediate bow, telescopic arms pivotally connected to said intermediate bow and the ends of said outrigger bow, and means connecting said telescopic arms with 65 said rearwardly extending bow so that the forward end of said outrigger bow may be adjusted.

3. In a vehicle top, the combination of a rearwardly extending bow, pieces of hardware 70 carried thereby, an intermediate break-down bow pivotally connected to said pieces of hardware, an outrigger bow, links pivotally connected to said outrigger bow, and to said intermediate bow, telescopic arms pivotally connected to said intermediate bow and to the ends of said outrigger bow, and means connecting said telescopic arms to said pieces of hardware so that the rear ends 75 of said telescopic arms may be adjusted to 80 shift the forward end of said outrigger bow.

4. A vehicle top framework, comprising a body bow, an intermediate two-part break down bow having its rear part pivotally supported by said body bow, a supplemental bow pivotally mounted on the rear part 85 of said intermediate breakdown bow, an outrigger bow, arms supporting said outrigger bow and connected to said body bow above the rear part of said intermediate 90 breakdown bow, links connecting said outrigger bow to said supplemental bow, and links connecting said outrigger bow to the forward part of said intermediate breakdown bow, the links being set one in advance 95 of the other with the supplemental bow links intersecting the plane of the intermediate breakdown bow.

5. A vehicle top framework comprising a body bow, pieces of hardware, on said bow, 100 an intermediate break-down jointed bow pivotally connected to said pieces of hardware, an outrigger bow, and arms pivotally connected to said pieces of hardware above the pivotal connections of said intermediate 105 bow with said pieces of hardware, said arms being pivotally connected to said outrigger bow and to said intermediate bow in advance of the joints thereof, and each piece of hardware having series of openings permitting 110 of the arms being connected to said pieces of hardware so that the forward end of the outrigger bow may be adjusted.

In witness whereof I affix my signature in the presence of a witness.

WATSON MacKEWEN.

Witness:

KARL H. BUTLER.
